UNITED STATES PATENT OFFICE

2,514,712

CLOTHES-WASHING MACHINE

Harry Lundell, Chicago, Ill.

Application May 25, 1945, Serial No. 595,749

1 Claim. (CL. 68—43)

1

This invention relates to an improved washing machine which is preferably adapted for washing clothes and garments and which, while operable by mechanical means under certain circumstances, is here shown as of a hand operated type.

The invention, more specifically revealed, has to do with a tub type washer in which a plunger or reciprocatory pounder is alternately moved up and down in the tub, the head of the pounder being valved to more satisfactorily agitate and surge the water against and through the fibres of the garments.

More explicitly, I accomplish the end sought through the adoption and use of a tub including a major or main compartment, this to accommodate the valved reciprocatory plunger or pounder, said tub being provided at diametrically opposite sides with comparatively smaller flute-like extensions and these constituting spill-ways having valved communication at their lower portions with the main tub.

Novelty is, therefore, predicated upon the use of a plunger which is provided with valves, the valves opening on the down stroke, and closing on the up stroke, whereby to trap the water above the plunger and to carry it over into the end spill-ways, the water returning from the spill ways to the main tub by way of flap valves, and said flap valves being opened by the down rush of water as well as by the suction produced thereon through the up stroke of the plunger.

Other features and advantages will become more readily apparent from the following description and the accompanying illustrative drawings.

In the drawings, wherein like numerals are employed to designate like parts throughout the views:

Figure 1 is a top plan view of a washing machine constructed in accordance with the structural principles of the instant invention.

Figure 2 is a central vertical sectional view, with parts in elevation, this taken on the plane of the line 2—2 of Figure 1, looking in the direction of the arrows.

Figure 3 is a view at right angles, this through one end of the structure and said view being on the plane of the line 3—3 of Figure 1, looking in the direction of the arrows.

Figure 4 is a fragmentary detailed view, slightly enlarged, this to show the flap valve means and being on the line 4—4 of Figure 2, looking in the direction of the arrows.

Referring now to the drawings by distinguishing reference numerals, it will be seen that the

principal part of the invention is the tub. This is of appropriate material and dimensions, and the main or body portion thereof is denoted by the numeral 5. In top plan it is generally cylindrical in cross sectional form, being closed at the bottom and open at the top, the diametrically opposite sides thereof being flattened and having semi-cylindrical extensions 6 aligned therewith. The extensions are duplicate in construction and are open at their upper ends and closed at their lower ends. These extensions 6 constitute the aforementioned spill-ways. Water from the upper chamber 7 is carried over into the upper end of the spill-ways by way of the communicating passages 8. From these spill-ways the water returns to the lower chamber 9 of the main tub, this by way of check valves. The check valves in this instance are in the form of flaps 10, these being hinged in place as at 11. The valves are adapted to swing inwardly into the chamber 9.

The pounder-type plunger comprises a head plate 12 of general disc-like form having flattened ends 12a in slidable contact with the correspondingly proportioned and shaped flattened ends of the main tub. The head is reciprocated up and down by a shaft or rod 13. In the present instance, this is a manually operated handle. However, in practice it could be a shaft driven from a mechanical source of power (not shown). The handle is secured as at 14 to the central portion of the disc-like head. The head is provided with equi-distant ports or passages 15 having disc-like flap valves 16, these arranged on the top of the head plate and being hinged in place on one side, as at the points 17.

In Figure 2 I have shown a drain port at the point 18 but this is an optional feature. That is to say, if such a port is actually provided it will, of course, be closed by a suitable insertible and removable plug (not shown). However, this port need not be here as the tub can be drained by dumping, if desired.

In practice the clothes are placed in the water in the main compartment 9 and a handle 13 of the plunger is moved up and down in the chambers 7 and 9. On the down stroke sufficient pressure is exerted against the head of the body of water to drive water through the articles of apparel, this in a well known manner. When the plunger is moved upwardly, the flap valves 16 are closed and this lifts the column of water in the chamber 7 up and it spills over into the spill-ways 6 by way of the discharge or communicating passages 8. The returning water finds its

way back to the main chamber or tub 9 by way of the flap valves 10. These are opened partly by downward pressure of the water against the outer sides and also by the suction exerted thereagainst as the plunger is lifted up in the chamber 8.

It is submitted that a washing machine constructed in accordance with the structural principles herein shown and described is aptly fitted for the purposes intended, is simple and expedient, and otherwise suitable to achieve the desired ends.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and arrangement of parts may be resorted to in actual practice so long as no departure is made from the invention as claimed.

I claim:

A washing machine of the class described comprising a circular open top tub having an annular vertical rim provided with diametrically opposite vertically extending semi-cylindrical outstanding flutes defining, in conjunction with the tub, main and auxiliary compartments, vertically disposed partition walls mounted in the respective flutes and situated between said compartments and converting said flutes into spillways for returning water, said partition walls being flat from top to bottom, the upper end portions of the partition walls having notches and

said notches being on a plane below the open top of said tub and forming overflow passages leading from the main compartment to the spillways, the lower end portions of said partition walls being apertured adjacent the tub bottom to provide water returns leading from the spillways back into the main compartment, flap valves hingedly mounted for swinging on said partition walls and normally closing said apertures, a plunger comprising a head fitted snugly in said main compartment, diametrically opposite marginal edge portions of said head being flattened and in movable contact with said correspondingly flat partition walls, said head being provided with ports, and flap valves hingedly mounted on the upper surface of said head and serving to close the ports, the last-named valves being adapted to open on the down-stroke of the plunger and adapted to close automatically on the up-stroke of said plunger.
